UNITED STATES PATENT OFFICE

EDWARD P. FABER, OF CHICAGO, ILLINOIS

HUMIDIFIER

Application filed February 1, 1928. Serial No. 251,025.

The invention relates to humidifiers and is especially adapted for use in connection with a hot air register whereby the air which enters a room through the register will be 5 moistened.

The main object of the invention is to provide a humidifier of the above mentioned character which may be readily and easily secured to a heat register, the same being disposed on the side of the register adjacent the hot air flue, and is also adapted to act as the closure means for the said register.

Another object of the invention is to provide a humidifier of the above mentioned 15 character which may be pivotally connected to a heat register, the same being so disposed as to be concealed from view from the interior of the room containing the said register.

20 A further object of the invention is to provide a humidifier of the character described which is adapted for hinged engagement with the inner face of a heat register in place of the usual closure member therefor, the said humidifier being adapted for regulating the admission of hot air to the room in which the register is located as well as moistening the air passing through the said register.

A still further object of the invention is to 25 provide a humidifier of the above mentioned character comprising a liquid containing receptacle having means associated therewith for indicating the level of the liquid contained therein.

30 A still further object of the invention is to provide a humidifier of the character described having means for hingedly engaging a heat register on the inner face thereof whereby the said humidifier may act as a closure means for said register, the said humidifier being connected to said register without necessitating any alteration of the wall in which the register is located.

35 A still further object of the invention is to provide a humidifier of the character described having a main liquid containing receptacle and an auxiliary liquid container rigidly and fixedly secured to one face thereof, and having communication therewith, the said auxiliary container being constructed

of a material having a higher heat conductivity than that from which the main receptacle is constructed whereby a more rapid evaporation of the liquid therein is obtained.

40 A still further object of the invention is to provide a humidifier of the character described adapted for association with a heat register for moistening the air passing therethrough, and comprising a main liquid receptacle and an auxiliary liquid container secured to one face thereof, and means associated with said auxiliary container for causing a more rapid evaporation of the liquid contained therein.

45 A still further object of the invention is to provide a humidifier of the above named character which may be readily and easily associated with a heat register for moistening the air passing therethrough, the same being further simple in construction, inexpensive, neat in appearance, compact, strong and durable, and further well adapted to the purpose for which it is designed.

50 Stated generally, the invention comprises a liquid containing receptacle of substantially 55 right triangular cross section hingedly connected to the inner face of a wall heat register of any suitable type and being adapted for regulating the passage of heat therethrough. The said receptacle being provided on the forward face thereof with an auxiliary liquid container constructed of copper or the like, the said auxiliary container having communication with the main receptacle, and having means associated therewith for causing a 60 more rapid evaporation of the liquid contained therein. The main receptacle being also provided with a filler opening and level indicating means for visibly indicating the 65 level of the liquid in the containers.

70 The invention is capable of receiving a variety of mechanical expressions. While, for the purpose of illustration, two specific embodiments of the invention have been shown in the accompanying drawings and described 75 with considerable particularity in the description herein, it is to be expressly understood that such specific embodiments are for purposes of illustration only, and are not to 80 be construed as a definition of the limits of 85 90 95 100

the invention, reference being had to the appended claims for that purpose.

With the foregoing and other objects in view, which will appear as the description proceeds, my invention consists in the construction, arrangement and combination of parts of my apparatus whereby the objects contemplated are attained, as hereinafter more fully set forth, pointed out in the appended claims, and illustrated in the accompanying drawings, in which:—

Fig. 1, is a central cross sectional view of a wall heat register having an embodiment of the invention associated therewith;

Fig. 2, is a front elevational view of the same;

Fig. 3, is a central cross sectional view of a humidifier embodying the invention;

Fig. 4, is a front elevational view of the same, parts thereof being broken away; and

Figs. 5 and 6, are cross sectional and front elevational views respectively of a modified form of the invention.

In the drawings, wherein for the purpose of illustration are shown the preferred embodiments of the invention, the numeral 10, designates a heat register of usual and well known construction, mounted in the usual manner in the wall 12, of a room, said register having the grating 11, which is positioned in an opening provided therefor in said wall 12, said opening communicating with the hot air flue 13. In place of the usual hinged closure member provided in registers of this type for regulating the admission of heat to the room, I provide a humidifier generally designated by the reference character 14, said humidifier being pivotally hinged to the upper portion of the inner face of the grating 11, as shown at 15, by means of hinges 16, or in any other suitable manner.

The humidifier 14, comprises a liquid containing receptacle 18, of substantially right triangular cross section, the apex of the triangle being at the lower portion, and the hypotenuse thereof being the rear face of the receptacle. The front face 17, of the receptacle is disposed in a substantially vertical plane, and is adapted to be moved to open and close the openings in the grating 11, for regulating the passage of heat through the register into the room. The receptacle 18, may be, if desired, formed from a single sheet of material, such as brass, or the like, said receptacle being closed on all sides, by means of a seam 19, or the like, as shown in Fig. 3, said seam being made water tight for preventing leakage of water therethrough. In the front face 17, near the upper portion thereof, a plurality of openings 20, for venting the chamber 18, are provided. Also, a filling opening 21, through which the chamber 18, may be filled through the openings in the grating 11, is provided in the front face 17, near the upper portion thereof.

In order to cause a more rapid evaporation of the liquid in the humidifier, I provide on the front face 17, thereof, an auxiliary liquid container 22, said container being relatively flat and substantially rectangular in form, and of a size somewhat smaller than the size of the front face 17. The container 22, is constructed from a material possessing a high heat conductivity, such as copper or the like, and is open at the top for permitting the ready escape of vapor formed therein. In the form illustrated, the container 22, is rigidly and fixedly secured in spaced relation and parallel to the front face 17, in any well known and suitable manner, such as by soldering the four corners of the container to the front face 17, as shown at 23. In order to establish communication between the auxiliary container and the receptacle 18, one or both of the lower soldered corners 23, may be bored to provide the passage 24, leading from the receptacle 18, to the bottom portion of the container, thus permitting the liquid in the chamber 18, to flow into and to rise to the same level in the container 22. One or both of the soldered upper corners 23, may be bored to provide the passage 25, for providing an overflow opening from the container 22, into the receptacle 18, thus preventing the spilling over of liquid from the auxiliary container.

For the purpose of causing a more rapid evaporation of the liquid contained in the auxiliary container, I dispose within said container a screening 26, of copper or the like, said screening completely filling the container. The action of the screening will be readily understood by those skilled in the art. Said screening will not only separate the liquid into small particles which will be more readily evaporated, but will also tend to vibrate upon being heated, thus tending to cause a stirring up of the liquid particles, thereby causing a more rapid evaporation of the liquid. By spacing the container 22, from the front face 17, the said auxiliary container will be at all times completely surrounded by the hot air passing through the flue 13, thereby thoroughly heating the same.

An operating handle 28, of suitable construction having means thereon for engagement with a portion of the grating 11, is provided for holding the said humidifier in a plurality of positions. In the illustration shown in Fig. 1, the humidifier is held in position for closing the openings in the grating 11, thereby preventing the passage of heat from the hot air flue 13, into the room through the register. When it is desired to open the register the operating handle 28, is actuated to move the humidifier about the hinges 16, any desired amount, the said handle engaging a portion of the grating 11, for holding the said humidifier in the desired open position. It will thus be seen that the humidifier is not

only adapted for moistening the air passing through the register into the room, but also acts as a closure means for regulating the passage of heat into the room.

If desired, means may be provided for visibly indicating the level of the liquid within the humidifier. In the embodiment illustrated, the indicating means comprises a float member 30, of cork, or any other material suitable for that purpose, said float member being mounted on one end of a rod 31, the other end of said rod 31, being rigidly secured to a transverse rod 32, intermediate the ends thereof, said rod 32, being mounted for pivotal movement in the front and rear faces of the receptacle 18. The forward end of the rod 32, may be bent at right angles to provide the pointer 33, which pointer cooperates with designations marked on the front face 17, for visibly indicating the level of the liquid in the humidifier. The rear end of the rod 32, may also be bent a slight amount to prevent the said rod from being displaced or moved from its assembled operative position. When the pointer 33, is opposite the designation marked "F" on the front face 17, the receptacle will be filled with a maximum amount of liquid, the level of which will be immediately below the passage 25, leading from the auxiliary container to the receptacle 18, so as to prevent the overflow of liquid through the top of the container 22.

It will thus be noted that I provide a humidifying means which is adapted for attachment to a wall heat register of the usual type, without altering the wall in which the register is located, said humidifying means also acting as a means for regulating the admission of heat into the room in which the register is located. It will also be noted that by providing the auxiliary container a more rapid evaporation of the liquid is obtained, thus assuring a better and more efficient moistening of the air. Also, the said humidifying means is so disposed when in assembled position with the register as to be entirely concealed from view from the interior of the room containing the register.

In Figs. 5, and 6, of the drawings, a modified form of the invention is illustrated. In this form, the humidifier is constructed of a single piece of metal possessing a high heat conductivity, such as copper, or the like, which is adapted to cause a rapid evaporation of the liquid contained therein. In the form illustrated, the reference character 40, designates generally a humidifier which may be attached to a wall heat register of the usual type in a manner similar to that illustrated and described in connection with the modification illustrated in Figs. 3, and 4. The device is hingedly secured to the register by means of the hinges 41, and is also provided with an operating handle 28, similar to the one shown in Fig. 1, for operating the humidifier to open and close the openings in the grating 11.

The humidifying means 40, comprises the receptacle 42, which is substantially right triangular in cross section, the apex of the triangle being at the lower end thereof, and the hypotenuse at the rear. The front face 43, is disposed in a substantially vertical plane, so as to adapt it for opening and closing the openings in the grating 11. The receptacle 42, is made out of a single sheet of material, such as copper or the like, and is closed at the rear by means of the seam shown at 44, which seam is made water tight to prevent the leakage of water therethrough. A slotted opening 45, extending substantially the full width of the receptacle near the upper portion thereof, is provided, in the front face 43, said slotted opening providing the means through which the said receptacle may be filled with liquid, and also through which the vapor formed in said receptacle may escape into the room for moistening the air therein.

If desired, pockets for receiving copper screening similar to that positioned in the auxiliary container 22, may be provided on the sides of the receptacle 42, for causing a more rapid evaporation of the liquid contained therein.

It will thus be noted that the modified form of humidifier illustrated in Figs. 5, and 6, is simple, compact, neat in appearance, easily and readily installed, and is adapted for attachment with a wall heat register of the usual type without necessitating the alteration of the wall, and which will be at all times practical and efficient for carrying out the purpose for which it is designed.

While the illustrated embodiments have been described with considerable particularity, it is to be expressly understood that the invention is not to be restricted to the particular form shown, as parts thereof are capable of use without other parts thereof, as various modifications and embodiments will readily suggest themselves to those skilled in the art. Reference being had to the appended claims in determining the limits of the invention.

What I claim and desire to secure by Letters Patent of the United States is:—

1. In a device of the character described, the combination with a heat register, of means for moistening the air passing therethrough associated therewith, said means comprising a liquid containing receptacle adapted for regulating the passage of heat through the register.

2. In a device of the character described, the combination with a heat register, of means associated therewith for regulating the passage of heat therethrough, said means comprising a liquid containing receptacle adapted for moistening the air passing into the room, and being mounted on the side of said

register adjacent the hot air flue, whereby the said means will be concealed from view from the interior of the room in which the register is located.

5. In a device of the character described, the combination with a heat register, of means associated therewith for regulating the passage of heat therethrough, said means comprising a liquid containing receptacle having the front face thereof lying in a substantially vertical plane for cooperating with the register for opening and closing the same, and being adapted for moistening the air passing into the room, said means being disposed on 10 the side of the register adjacent the hot air flue, whereby the same may be concealed from view from the interior of the room in which the register is located.

4. In a device of the character described, 20 the combination with a hot air register, of means associated therewith for moistening the air passing therethrough, said means comprising a liquid containing receptacle of a substantial right triangular cross section, the 25 front face of which being disposed in a substantially vertical plane for cooperating with the grating of the register for regulating the passage of heat therethrough into the room, and means carried by said receptacle for engagement with a portion of said grating for holding the said receptacle in a plurality of 30 positions.

5. In a device of the character described, the combination with a heat register, of humidifying means associated therewith for moistening the air passing therethrough, said humidifying means comprising a liquid containing receptacle of substantially right triangular cross section, and having the front 35 face thereof disposed in a substantially vertical plane for cooperating with the said register for regulating the passage of heat therethrough, said receptacle being secured to said register so as to be concealed from 40 view from the interior of the room in which the same is located, and means provided in the front face of said receptacle for filling the same with liquid.

6. In a device of the character described, 50 the combination with a hot air register, of humidifying means for moistening the air passing therethrough associated therewith, said means comprising a liquid containing receptacle, the front face of which is adapted 55 for regulating the passage of heat through the register, said receptacle being pivotally secured to said register on the inner face thereof, whereby the same will be entirely concealed from view from the interior of the 60 room containing the register, means provided for filling the receptacle with liquid from the inside of the room, and means carried by said receptacle for engagement with a portion of said register for holding the said receptacle 65 in a plurality of positions.

7. In a device of the character described, the combination of a hot air register, and humidifying means for moistening the air passing therethrough associated therewith, said humidifying means comprising a main liquid containing receptacle also adapted for regulating the passage of heat through the register and an auxiliary liquid container rigidly secured to one face thereof, said auxiliary container being spaced from and parallel to the face to which it is secured, whereby the said auxiliary container may be completely surrounded by the hot air passing through the register, and means for establishing communication between the said main receptacle and the auxiliary container.

8. In a device of the character described, the combination with a hot air register, of humidifying means for moistening the air passing through the register associated therewith, said humidifying means comprising a main liquid containing receptacle the front face of which is adapted for regulating the passage of heat through the register, an auxiliary liquid container rigidly secured in spaced and parallel relation to said front face, and communicating with said main receptacle, said auxiliary container being constructed of material possessing a higher heat conductivity than that from which the main receptacle is constructed, for causing a more rapid evaporation therein, and means provided in said humidifying means for supplying liquid thereto from the inside of the room.

9. In a device of the character described, the combination of a hot air register, and humidifying means for moistening the air passing through the register associated therewith, said humidifying means comprising a main liquid containing receptacle the front face of which is adapted for cooperation with the register to regulate the passage of heat therethrough, operating means for moving and holding said humidifying means in a plurality of positions, an auxiliary liquid container rigidly secured to said front face in spaced and parallel relation thereto, whereby the same may be completely surrounded by the hot air passing through the register, means for establishing communication between the lower portion of said auxiliary container and said receptacle, and means disposed in said auxiliary container for causing a more rapid evaporation of the liquid contained therein, said means comprising a screening of a metal possessing a high heat conductivity.

10. In a device of the character described, the combination with a hot air register, and a humidifying means associated therewith for moistening the air passing therethrough, said humidifying means comprising a main liquid containing receptacle, the front face of which is adapted for cooperation with the register for regulating the passage of heat

therethrough, an auxiliary liquid container rigidly secured to said front face in spaced and parallel relation thereto, means of communication between the lower portion of the auxiliary container and the main receptacle, overflow means leading from the upper portion of the auxiliary container into the main receptacle, means for filling the said main receptacle, and means associated with said main receptacle for indicating the level of liquid contained therein.

11. The combination of a heat register, a movable damper therefor, said damper comprising a liquid containing receptacle for moistening the air passing through the register.

15 In testimony whereof I affix my signature.
EDWARD P. FABER.
